WELL TOOL

Alfred Muhlbach, Los Angeles, Calif.

Application May 8, 1940, Serial No. 333,983

11 Claims. (Cl. 294—116)

This invention relates to a device adapted to be lowered into a well that is being drilled, to cooperate with tools or other apparatus, in the well. Such tools so positioned are often without means of conveniently raising them to the surface. The present device can form a connection therewith, by means of which the tool or apparatus may be brought to the surface. Such devices are known and are commonly termed "overshots."

In present day drilling practice, wire line core barrels are frequently used. Such core barrels are detachably secured in the end of the drill string so as to be rotated and advanced therewith and are removed whenever desired by means of a tool or overshot which is lowered in the drill string on a cable, and is adapted to grasp the top of the core barrel by any of various types of latching means.

It sometimes happens that the core barrel or other apparatus becomes stuck in position in the well or casing, as for instance, due to small rocks wedging about the apparatus, or other causes. When this occurs, the wire line and overshot are in the drill pipe and can not be removed, since they have been attached to the core barrel. At the same time their presence there seriously impedes any steps it may be desired to take to loosen the core barrel or other apparatus so that it can be removed. Frequently, efforts to lift a stuck core barrel result in parting the wire line, after which there is nothing to do but remove the entire drill string, which is always an expensive job, usually attended by considerable risk.

By the aid of the present invention, the connection between the wire line and the core barrel, or other apparatus which it is desired to lift, is arranged to be broken when the pull on the cable reaches some predetermined amount, well within the capacity of the cable. Thus, if it is not possible to move the core barrel or "fish" without endangering the cable, the overshot is released and together with the cable is removed from the well, when appropriate steps to loosen the core barrel may be taken readily.

It is accordingly one of the objects of this invention to provide an overshot capable of releasing its grip in response to a pull of a predetermined magnitude.

It is another object of this invention to provide a releasable overshot which is strong, simple and durable.

It is still another object of this invention to provide a releasable overshot in which the pull

acts directly to release the overshot, after this pull has reached a certain magnitude.

It is still further an object of this invention to provide an overshot in which the overshot is released in response to the shearing of a pin by the lifting force exerted on the overshot.

This invention possesses many other advantages, and has other objects which may be made more easily apparent from a consideration of several embodiments of the invention. For this purpose there are shown a few forms in the drawings accompanying and forming part of the present specification. These forms will now be described in detail, illustrating the general principles of the invention; but it is to be understood that this detailed description is not to be taken in a limiting sense, since the scope of the invention is best defined by the appended claims.

In the drawings:

Figure 1 is a longitudinal section through a tool, embodying the invention, and connected to the upper end of a core barrel or other apparatus preparatory to lifting it from the well;

Fig. 2 is a sectional view, on an enlarged scale, taken on plane 2—2 of Fig. 1;

Fig. 3 is a view similar to Fig. 1, but showing the tool just after it has released the core barrel;

Fig. 4 is a view similar to Fig. 1 but showing a modified form of the invention;

Fig. 5 is a sectional view, on an enlarged scale, as seen on plane 5—5 of Fig. 4;

Fig. 6 is a view showing the tool of Fig. 4 just after releasing the core barrel;

Fig. 7 is a fragmentary view similar to Fig. 4, but showing a further modified form of the invention;

Fig. 8 is a view showing the operation of resetting the tool of Fig. 1; and

Fig. 9 is a section as seen on plane 9—9 of Fig. 8.

Referring to the form of the invention shown in Figs. 1, 2 and 3, the tool or overshot is generally indicated by 1 and is suspended from a wire line or cable 2 provided with a suitable socket or threaded member 3. A sinker bar 4 to insure the tool traveling downwardly through the mud laden fluid of the well may also be provided.

The lower end of the tool 1 is provided with a pair of pivoted jaw or hook members 5 and 6 which are urged toward engaging position by a spring 7. These jaws are adapted to engage under a shoulder 8 provided at the upper end of the core barrel 9. With the core barrel in place, when the tool 1 is lowered to it, the jaws 5 and 6 engage shoulder 8 so that the core barrel 9

may be lifted out of the well by means of cable 2. Such arrangements are known; however, it will be apparent that in event it is not possible to move the core barrel, it is desirable to be able to release the jaws so that the cable 2 and tool 1 may be removed.

To make such removal possible, the tool 1 has a body 10 within which a mandrel 11 is telescopically mounted for limited longitudinal movement with respect thereto. The arrangement is such that when there is relative axial movement of the mandrel 11 in the bore 16 of body 10, the jaws 5, 6 carried by the mandrel are released from shoulder 8. Normally such relative movement of the mandrel 11 and the body 10 is prevented, since they are joined by a releasable or frangible connection, such as shear pin 12. The lifting force exerted by cable 2 is transmitted to the mandrel 11 and hence to core barrel 9 by this connection. If the core barrel is not readily moved, when the force exerted by cable 2 becomes sufficient to fracture the connection 12, mandrel 11 is permitted to move to its extended position (Fig. 3) and the jaws 5, 6 release the core barrel 9, in a manner now to be described.

Body 10 has a threaded tapered pin 15 at its upper end by means of which the tool is attached to the cable 2, and its bore 16 extends to its lower end. The upper part 17 of mandrel 11 is slideable within bore 16. The lower portion of mandrel 11 is provided with a bore or bowl 18 intersected by slot 19, the latter accommodating jaws 5 and 6 which are pivoted on pin 20 in the mandrel 11. Jaw members 5 and 6 each have upward extensions 21 and 22 between which spring 7 is accommodated and are provided with exterior inclined or cam surfaces 23 and 24. Jaw members 5 and 6 also have downward extensions 25 and 26, each provided with an inwardly and upwardly directed hook 27, 28, adapted to enter bowl 18.

The upper end of the core barrel or other apparatus 9 is shown as having a tapered portion 70, terminating in a neck 71 of relatively small diameter and surmounted by a head 72, thus forming shoulder 8. The top of head 72 is convex as indicated by 73 and the lower end of bore 18 is flared outwardly as indicated by 74. Thus, as the lower end of the tool 1 contacts head 72, surfaces 73 and 74 cooperate to guide the tool into coaxial position with apparatus 9 so that head 72 enters bowl 18 and engages jaws 5 and 6. Continued lowering of tool 1 causes the lower inclined surfaces 75 and 76 of the jaws 5, 6 to engage head 72, and the jaws are forced apart. Thus the jaws pass downwardly over the head until the hook portions 27 and 28 are forced under shoulder 8 by spring 7.

A collar 30 is mounted on the outside of body 10, being secured against longitudinal movement on the body by pin 12, which pin, as clearly shown in Fig. 2, passes through body 10, mandrel 11 and collar 30, preventing relative movement between them. A second collar 31 also on the outside of body 10 is secured against movement with respect to mandrel 11 by a pin 32. As clearly shown in Fig. 2 this pin 32 extends through mandrel 11, body 10 and ring 31, but is utilized to form a lost motion connection between the mandrel and the body by the provision of slots 33 in the body 10.

A compression spring 34 is confined between collars 30 and 31. It will be plain that relative movement between these collars is prevented by their being secured to mandrel 11 by pins 12 and

32 respectively. However, if pin 12 is fractured, collar 30 will be forced downwardly on the mandrel 11, the lower edge of collar 30 riding downwardly on surfaces 23 and 24 forcing jaws 5 and 6 to the disengaged position of Fig. 3.

From a consideration of Fig. 2, it will be clear that any upward force exerted as by cable 2 on body 10 is transmitted to the mandrel 11, and hence to whatever is anchored between the jaws 5, 6, solely through the connecting pin 12. When this force is sufficient to fracture this pin, body 10 moves upwardly on mandrel 11 until the lower end of slots 33 engage pin 32 (see Fig. 3). At the same time, collar 30 being freed of the restraint of pin 12 is forced downwardly of the mandrel 11 by spring 34 and swings jaw member 5, 6, about their pivot 20 to free hooks 27, 28 from shoulder 8. The tool 1 may now be withdrawn from the well, and suitable steps taken to loosen the core barrel or other apparatus 9. The parts of tool 1 may be readily returned to their initial relative positions, and a new pin 12 inserted, after which the tool is ready for further use.

A convenient means of compressing the operating spring 34, so that the tool may be reset and a new pin 12 replaced is provided by the arrangement shown in Figs. 8 and 9. Therein a plate 90 is provided with a U-shaped opening 91 just large enough to accommodate the mandrel 11 below collar 30. Plate 90 may be supported in any convenient manner, as for example by a section of pipe 92 partly cut away to receive the tool as at 93 and provided with a base 94. While the tool 1 is attached to cable 2 and sinker bar 4, it is inserted transversely into pipe 92 through opening 93, the lower end of collar 30 being slightly above plate 90. Tool 1 is then lowered so that collar 30 rests on plate 90, the weight of sinker bar 4 being sufficient to compress spring 34 to its initial condition and allowing all parts to return to their original position as shown in Fig. 1. A new pin 12 is then passed through collar 30, mandrel 11 and body 10 to retain them in position. This pin 12 may be retained in place in any convenient way, as by riveting over the ends slightly.

In the form of the invention illustrated in Figs. 4, 5 and 6, the tool 50 is attached to a cable 2 in the same manner as before, and is arranged to grasp the core barrel or other apparatus 9 by a pair of pivoted jaw members 51 and 52 in a similar manner.

Tool 50 comprises a body member 53, attached to cable 2, having a bore 54 within which is slidably mounted a mandrel 55 carrying the jaws 51, 52 in a slot in its lower portion. A pin 56 secured in body 53 engages a slot 57 in the mandrel providing a lost motion connection between the body and the mandrel. A shear pin 58 releasably secures the mandrel 55 to body 53 at the upper limit of the movement permitted by the slot and pin connection 57, 56.

Body 53 has a skirt or extension 60 which encircles the upper portions 61, 62 of jaw members 51, 52. These portions 61, 62 have lobes or cheeks 63, 64, providing cam surfaces 65, 66. Skirt 60 has openings 67 and 68 to accommodate lobes 63, 64 respectively, the lower edges of these openings being adapted to cooperate with cam surfaces 65, 66.

With body 53 and mandrel 55 locked together by pin 58, jaw members 51 and 52 are free to swing apart to receive the head 72 and to close in response to compression spring 69 to engage

shoulder 8. As long as the upward pull exerted by cable 2 is not sufficient to fracture the pin 58, the jaws will remain engaged with the shoulder 8, and under normal conditions the core barrel or other apparatus 9 may thus be lifted out of the well. If, however, this force becomes excessive and the pin 58 is fractured, body 53 will slide upwards on mandrel 55 until stopped by the engagement of pin 56 with the top of slot 57.

This relative movement between body 53 and mandrel 55 causes the lower surfaces of openings 67 and 68 to act on surfaces 65, 66, forcing the upper portions of jaw members 51 and 52 inwardly and swinging the lower portions outwardly and free of shoulder 8. The tool 50 is thus entirely disconnected from the core barrel 9 and may be removed from the well.

In the modification shown in Fig. 7, a spring retainer is provided to maintain the mandrel and body against relative movement until the force tending to cause this movement reaches a predetermined amount. Thus, mandrel 80 is substantially identical with mandrel 55; it carries jaw members 51 and 52 and is connected to the body 81 by a lost motion connection 56, 57 all as before. The exterior of mandrel 80 has a circumferential groove 82 which registers with an internal groove 83 in body 81, when the body and mandrel are positioned to permit jaws 51, 52 to close. A split ring, or snap ring 84 is disposed in groove 83 and due to its resilience embraces mandrel 80 and engages groove 82. Due to the simultaneous engagement of grooves 82 and 83 by ring 84, relative motion between the body 81 and mandrel 80 is prevented. The upper and lower surfaces of groove 82 are bevelled, as indicated by 85, 86. The inner portions of the end surfaces of ring 84 are similarly bevelled, thus upon the exertion of sufficient upward force on body 81, assuming mandrel 80 being fixed to resist it, ring 84 will be forced out of groove 82 so that it is entirely in groove 83, allowing the body to slip upwardly along the mandrel. This produces the same result as the shearing of pin 58.

This form of the tool may be reset by suitably supporting the lower end of the mandrel 80 and applying a downward force on the body 81, as by the weight of sinker bar 4. When ring 84 is out of engagement with groove 82, it is only necessary to apply sufficient force on the body 81 to overcome the frictional grip of ring 84 on mandrel 80 to cause relative movement. Hence, a force much smaller than that necessary to trip the tool suffices to reset it.

To permit the installation of ring 84 in the first place as well as its removal and replacement, body 81 is divided into sections 87 and 88 at groove 83, these sections being joined by the threaded connection 89.

What is claimed is:

1. In a device of the character described, a body adapted for longitudinal movement in a well bore, a mandrel carried by the body and in telescopic relationship therewith, said mandrel extending below the body and forming a bowl, open at the bottom, adapted to be placed over apparatus in a well, a releasable connection between the body and the mandrel to prevent relative movement therebetween, jaw members carried by the mandrel below the body and adapted to engage said apparatus so that said apparatus may be lifted from the well with said body, and means operative upon release of said releasable connection to disengage the jaw members from

the apparatus, said releasable connection being adapted to permit relative movement between the body and the mandrel when the upward force exerted on the body reaches a predetermined amount.

2. In a device of the character described, a body adapted for longitudinal movement in a well bore, a mandrel carried by the body and in telescopic relationship therewith, a releasable connection between the body and the mandrel to prevent relative movement therebetween, a pair of jaw members pivotally mounted on the mandrel, said jaw members having downward extensions adapted to move inwardly to engaging position, said members also having upward extensions with cam surfaces formed thereon, and a member having surfaces arranged to cooperate with said cam surfaces and movable along the mandrel upon release of said connection, said movement causing the jaw members to swing about their pivots and move the downward extensions out of engaging position.

3. In a device of the character described, a body, a mandrel having a bowl, open at the lower end of the mandrel, jaw members pivotally carried by the mandrel and adapted to engage an object in the bowl, spring means urging the jaws to engaging position, a member slidably on the mandrel and arranged to disengage the jaws, a shear pin for securing the member to the mandrel as well as for securing the mandrel to the body, and means forming a lost motion connection between the body and the mandrel to limit motion therebetween upon fracture of the shear pin.

4. In a device of the character described, a body having a bore, a mandrel having an extension slidably in said bore, a bowl at the lower end of the mandrel, jaw members pivoted in the mandrel and having depending extensions with respectively upwardly and oppositely directed hooks, resilient means urging the jaws about their pivots, so that the hooks enter the bowl, the jaw members also having upward extensions with cam surfaces thereon, means forming a cam follower movable with respect to the body and adapted to urge the jaw members about their pivots so that the hooks move away from each other and out of the bowl, means to move said follower with respect to the body, and means to prevent said movement until the force tending to cause relative movement between the body and the mandrel reaches a predetermined value.

5. In a device of the character described, a body arranged for longitudinal movement in a well bore, a mandrel, a frangible connection between the body and the mandrel for transmitting a lifting force from the body to the mandrel, means pivotally secured to the mandrel arranged to engage an object to be lifted in the well bore in response to upward movement of said body, means to disengage said last mentioned means upon breaking said connection and operated by continued upward movement of the body, and supplemental means to transmit the lifting force from the body to the mandrel after said connection is broken.

6. In a device of the character described, a body arranged for longitudinal movement in a well bore, a mandrel, a frangible connection between the body and the mandrel for transmitting a lifting force from the body to the mandrel, means pivotally secured to the mandrel arranged to engage an object to be lifted in the

well bore in response to upward movement of said body, a member movable upon said mandrel upon breaking said connection to disengage said engaging means, supplemental means to transmit the lifting force from the body to the mandrel after said connection is broken, said frangible connection also serving to prevent relative movement between the member and the mandrel.

7. In a device of the character described, a body arranged for longitudinal movement in a well bore, a mandrel, a frangible connection between the body and the mandrel for transmitting a lifting force from the body to the mandrel, means pivotally secured to the mandrel arranged to engage an object to be lifted in the well bore in response to upward movement of said body, said body being upwardly movable upon said mandrel to release said engaging means.

8. In a device of the character described, a mandrel, spring operated jaws pivoted on the mandrel and having cam surfaces, a member adapted for longitudinal movement along the mandrel, and having a surface to cooperate with the cam surfaces, upon such longitudinal movement to swing the jaws against the spring, means for exerting an upward pull on the mandrel and a shear pin through which such pull is exerted, said shear pin also serving to prevent longitudinal movement between the member and the mandrel, until said pin is sheared by said pull.

9. An overshot for retrieving a wire line core barrel including a member having a bowl adapted to receive a head formed on the core barrel, said head having a downwardly directed shoulder, latch means carried by said member and adapted to engage said shoulder when the head passes into said bowl, a body slideable with respect to said member, a collar slideable with respect to the member, a frangible connection be-

tween the body, the member and the collar to prevent relative movement therebetween, means adapted to cause the collar to slide on said member and release the latch means upon fracture of said connection, and means forming a lost motion connection between the body and the member to restrict relative motion between them after said connection is fractured.

10. An overshot for retrieving a wire line core barrel including a member having a bowl adapted to receive a head formed on the core barrel, said head having a downwardly directed shoulder, latch means carried by said member and adapted to engage said shoulder when the head passes into said bowl, a body slideable with respect to said member, said body having an extension about said member and engaging the latch means, said extension being adapted to disengage the latch means from said shoulder upon relative movement between the body and the member, a frangible connection between the body and the member to prevent such relative movement, and means to restrict movement between the body and the member after said frangible connection is broken.

11. In a device of the character described, a body, a mandrel carried by the body and arranged for limited longitudinal movement relative thereto, means carried by the mandrel for engaging a device in a well and normally urged to engaging position, means operative upon relative movement between the body and the mandrel to move the engaging means to disengaging position, and a resilient member joining the mandrel to the body to prevent such movement until the force tending to cause such movement reaches a predetermined amount.

ALFRED MUHLBACH.
